UNITED STATES PATENT OFFICE.

FREDERICK BENEDICT VOEGBELI, OF EASTON, PENNSYLVANIA.

CLOTH EXPANDER.

Application filed February 24, 1926. Serial No. 90,351.

The present invention relates to cloth expanders, and aims to provide a novel and improved mounting for a cloth expander to enable the expander to be conveniently moved into and out of contact with the cloth.

Another object of the invention is the provision of means for mounting a cloth expander between runs of cloth moving downwardly and upwardly, such as from one roll or drum downwardly into a dye jig and from such jig upwardly to another roll or drum, in order that the expander may be readily moved into contact with either of said runs of cloth or intermediate same.

With the foregoing and other objects in view, which will be apparent as the description proceeds, the invention resides in the construction and arrangement of parts as hereinafter described and claimed, it being understood that changes can be made within the scope of what is claimed, without departing from the spirit of the invention.

The invention is illustrated in the accompanying drawing, wherein—

Fig. 1 is a side elevation, somewhat diagrammatical, illustrating the invention as used in connection with a dye jig, portions being shown in section on the line 1—1 of Fig. 2.

Fig. 2 is a section on the line 2—2 of Fig. 1.

As illustrated, the cloth expander is used in connection with a dye jig, but the invention is not limited to such use, inasmuch as the expander mounting may be used for other purposes for which it is appropriate, such as for mounting an expander between oppositely moving runs of cloth to contact with either run of cloth.

As shown in the drawing, the cloth is unwound from the roll or drum 7 and passes downwardly, as at 8, under the guide rollers 9 and 10, and then moves upwardly, as at 12, to the roll or drum 13, for moving the cloth through a tank 11 containing the dye solution or other liquid with which the cloth is to be impregnated or treated. Ordinarily, it is necessary for an attendant to watch the cloth and manually keep the cloth from creasing and the selvedges doubling, which if permitted will permit the creases and selvedges to build up and eventually tear the cloth.

In order to eliminate the services of an attendant, and to keep the creases and dou-

bled selvedges out of the cloth, an expander 14 is mounted between the opposite runs 8 and 12 which move in opposite directions, the run 8 moving downwardly as shown and the run 12 moving upwardly. The expander may be of the kind disclosed in my Patent No. 1,569,343, granted January 12, 1926, or in my copending application Serial No. 65,337, filed Oct. 28, 1925, although any suitable cloth expander may be used. Such expander comprises a curved roller which, by its frictional contact with the cloth, will expand or stretch the cloth transversely.

The expander is supported by an oscillatory frame or support comprising arms 15 composed of sections of pipe having suitable fixtures or bearings 16 at their upper ends in which the terminals of the curved axle or rod of the expander are secured. The arms 15 have their lower ends mounted for rocking motion. As shown, said arms have T's 17 at their lower ends mounted for turning movement on a transverse rod or pipe 18 secured at its terminals to opposite sides of the tank 11. The arms 15 are connected by a brace 19, which may be a rod or section of pipe, with its ends connected to the arms 15 by T couplings 20.

Thus, as seen in Fig. 1, the expander support may be readily swung about the transverse axis of the rod or pipe 18 to the positions A, B and C. When the cloth is moving in the direction of the arrows as shown in Fig. 1, the expander is moved against the upwardly moving run 12, thereby stretching or expanding the cloth as it leaves the tank and before it is wound on the roll or drum 13. When the cloth moves in the opposite direction, the expander is moved to the position B, against the run 8, which in this case moves upwardly to the roll or drum 7, just reverse to the direction indicated by the arrows. In this way, the expander may be moved into contact with either of the opposite runs of cloth, according to the direction in which the cloth moves, so that a single expander will suffice for the purpose, using a simple mounting for the expander. The expander may be moved to the position C intermediate the runs of cloth when the use of the expander is not required or wanted, thereby rendering the expander idle.

When the expander is moved to either of the positions A and B, it will be noted that the expander will bear against the cloth

by its own weight, thereby maintaining the expander in position against the cloth and also applying the expander to the cloth under pressure, or the expander may be rigidly held in either position by any suitable means.

Having thus described the invention, what is claimed as new is:—

- 10 1. A curved cloth expander, and means for mounting same between opposite runs of cloth movable in either direction to contact with either of said runs with the convex side of the expander facing in the direction of travel of the cloth.
- 15 2. The combination with means for guiding cloth along opposite runs in either direction, a curved cloth expander between said runs, and means for mounting said expander to be moved into contact with either of said runs with the convex side of the expander facing in the direction of travel of the cloth.
- 20 3. A curved cloth expander, and an oscillatory support carrying said expander for the movement of the expander between opposite runs of cloth movable in either direction to contact with either run with the convex side of the expander facing in the direction of travel of the cloth.
- 25 4. The combination with means for guiding cloth along opposite runs in either direction.

tion, a curved cloth expander between said runs, and an oscillatory support carrying said expander for movement into contact with either of said runs with the convex side of the expander facing in the direction of travel of the cloth.

5. The combination with means for guiding cloth downwardly and upwardly along opposite runs in either direction, of a support mounted for oscillatory motion and extending upwardly from the axis of oscillation, and a curved cloth expander mounted on said support between said runs to contact with either of them with the convex side of the expander facing in the direction of travel of the cloth.

6. The combination with a tank and means for guiding cloth downwardly into and upwardly from said tank in either direction, of a support mounted for oscillatory movement in the tank and extending upwardly therefrom, and a curved cloth expander mounted on said support between said runs to contact with either of them with the convex side of the expander facing in the direction of travel of the cloth.

In testimony whereof I hereunto affix my signature.

FREDERICK BENEDICT VOEGELI.
